(57)

CLAIM

The ornamental design for a 6-way fitting, as shown and described.

DESCRIPTION

FIG. 1 is a front, right, top perspective view of the claimed design, the rear, left, bottom perspective view being identical thereto;

FIG. 2 is a front view of the claimed design of FIG. 1, the rear, left and right side views being identical thereto; and, FIG. 3 top view of the claimed design of FIG. 1, the bottom view being identical thereto.

Broken lines in the drawings illustrate portions of the 6-way and form no part of the claimed design.
